(57) **CLAIM**

The ornamental design for a handle, as shown and described.

DESCRIPTION

FIG. 1 is a front, top and right-side perspective view of a handle, showing the new design;

FIG. 2 is a front view thereof;

FIG. 3 is a left view thereof;

FIG. 4 is a right view thereof;

FIG. 5 is a top plan view of the handle, shown at an increased scale for clarity of disclosure;

FIG. 6 is a bottom plan view thereof;

FIG. 7 is a rear elevation view of the handle, shown at a typical scale; and,

FIG. 8 is a rear, top and right-side perspective view thereof. In the drawings, the broken line showing of a leash depicts environmental subject matter that forms part of the claimed design.

1 Claim, 8 Drawing Sheets
